US0D1016215S

(12) **United States Design Patent** (10) **Patent No.:** **US D1,016,215 S**
(45) **Date of Patent:** **** Feb. 27, 2024**

(54) **CONTROL UNIT FOR WATER PURIFIER**

(71) Applicant: **Bluewater Sweden AB**, Stockholm (SE)

(72) Inventors: **Bengt Rittri**, Stockholm (SE); **Magnus Lundström**, Stockholm (SE)

(73) Assignee: **BLUEWATER SWEDEN AB**, Stockholm (SE)

(**) Term: **15 Years**

(21) Appl. No.: **29/753,319**

(22) Filed: **Sep. 30, 2020**

(30) **Foreign Application Priority Data**

Mar. 31, 2020 (EM) 007779814

(51) **LOC (14) Cl.** **23-01**

(52) **U.S. Cl.**

USPC **D23/209**

(58) **Field of Classification Search**

(57) **CLAIM**

The ornamental design for a control unit for water purifier, as shown and described.

DESCRIPTION

FIG. 1 is a perspective top side view of a first example embodiment of a control unit for water purifier, showing the new design;

FIG. 2 is a perspective bottom side view of the first example embodiment of FIG. 1;

FIG. 3 is a first side view of the first example embodiment of FIG. 1;

FIG. 4 is a second side view of the first example embodiment of FIG. 1;

FIG. 5 is a third side view of the first example embodiment of FIG. 1;

FIG. 6 is a top view of the first example embodiment of FIG. 1; and,

FIG. 7 is a bottom view of the first example embodiment of FIG. 1.

The broken lines in drawing FIGS. 2 & 7 form no part of the claimed design.

1 Claim, 7 Drawing Sheets
